UNITED STATES PATENT OFFICE.

HARRY C. MONTGOMERY, OF CLEVELAND, OHIO.

DESIGN FOR A SINK-TRAP.

SPECIFICATION forming part of Design No. 21,873, dated September 27, 1892.

Application filed August 18, 1892. Serial No. 443,448. Term of patent 3½ years.

To all whom it may concern:

Be it known that I, HARRY C. MONTGOMERY, a citizen of the United States, residing in Cleveland, county of Cuyahoga, and State of Ohio, have invented and produced a new and useful Design in a Sink-Trap or Similar Article, and the following is a specification thereof, reference being had to the accompanying drawing, which shows a side elevation of my 5 newly-designed trap.

The leading features of the design are found in the shape or contour of the body of the trap, which may be described as consisting of two sections A and B. The lower or trap section proper is elbow-shaped on rounded lines 10

and has an ornamental pendant a. The upper section B is shaped substantially in the form of a vase with a base b at the point of union with the part A. An ornamental neck connection b² is formed on said part B, and the exterior surfaces of both parts A and B are plain and smooth, and said parts are cylindrical in cross-section throughout.

What I claim is—

The design in a sink-trap or similar article, 25 substantially as described.

HARRY C. MONTGOMERY.
